UNITED STATES PATENT OFFICE.

EMIL MEIER, OF NEW YORK, N. Y.

BRAKE ATTACHMENT FOR INK-ROLLERS.

SPECIFICATION forming part of Letters Patent No. 529,932, dated November 27, 1894.

Application filed December 28, 1893. Serial No. 494,930. (No model.)

To all whom it may concern:

Be it known that I, EMIL MEIER, of the city, county, and State of New York, have invented a new and Improved Brake Attachment for 5 Ink-Rollers, of which the following is a full, clear, and exact description.

My invention relates to improvements in printing presses and particularly to attachments for the ordinary angle or distributing 10 rollers. These, as it is well known, are usually made of glue and molasses, and have endwise as well as rotary movement and are turned by contact with the inking table. If 15 riders are used on the angle rollers, the increased heft causes the rollers to be struck with too great force by the table and they soon get out of shape, and if they are not used, the rollers, on account of their weight, turn freely after being struck by the table, so that 20 when the table, on its return stroke, comes in contact with the rollers, it meets them while the rollers are turning in the reverse direction to the movement of the table, and injurious friction results.

25 The object of my invention is to produce a very simple and inexpensive spring brake attachment, which may be applied to the shafts and angle rollers, which is adjustable so as to fit rollers arranged at different distances 30 apart, and which is adapted to clasp the shafts in such a manner as to permit the usual endwise and the necessary rotary movements of the rollers, but to prevent the rollers from rotating except when in actual contact with 35 the table.

To these ends my invention consists of certain features of construction and combinations of parts, which will be hereinafter described and claimed.

40 Reference is to be had to the accompanying drawings, forming a part of this specification, in which similar figures of reference indicate corresponding parts in all the views.

Figure 1 is a plan view of my improved 45 brake attachment as applied to the ordinary angle rollers, these being shown in their customary position adjacent to the reciprocating inking table of a printing press. Fig. 2 is a detail plan view of the attachment embodying my invention. Fig. 3 is an end elevation, partly in vertical section on the line 50 3-3 of Fig. 2, showing also the application

of the attachment to a pair of roller shafts; and Fig. 4 is a vertical section on the line 4-4 of Fig. 3.

The angle rollers 10 are of the usual kind and arranged in the customary way, being carried by shafts 11 which have reduced ends 12 forming the journals, these being hung in the slotted posts 13 on the press 14 in the usual manner, and the journals 12 are free to slide for a limited distance in the posts. The angle rollers contact with the table 15, which is exactly the usual kind, and which has at its front edge a swinging contact bar 15^a to first engage the rollers.

The rollers are usually arranged in pairs, and consequently I provide a spring brake attachment which is adapted to be applied to a pair of the roller shafts. In this attachment a pair of upper shoes 16 and lower shoes 17 are used, which are adapted to clasp the shafts 11, see Figs. 3 and 4, and as they are pressed together by a spring as described below, and the friction of the shoes on the shafts 75 is sufficient to stop the rotation of the shafts as soon as the rollers are out of contact with the table. The shoes 16 and 17 are carried by upper and lower plates or brackets 18 and 19, the former being bent downward in the middle, as shown at 20, so as to the better act 80 as a guide for the connecting bolt 21 which is fastened rigidly to the lower plate 19 and slides freely through the bent portion of the upper plate 18, the bolt having at its upper 85 end a head 22 between which and the lower portion of the bend 20, in the upper plate, is a spiral spring 23, which is coiled around the bolt and the pressure of which is sufficient to force the plates together hard enough to 90 cause the shoes 16 and 17 to press with considerable friction on the shafts 11, and thus when the shafts are set in motion by the table the shoes will stop them as soon as the table leaves the rollers. It will be seen that 95 the spring 23 may be made just strong enough to have the desired effect on the brake shoes.

The upper and lower plates 18 and 19 are slotted longitudinally near the ends, as shown at 24, and fastening screws 25 project through the slots and into the shoes 16 and 17, thus holding the shoes in place, and it will be seen that this arrangement enables the shoes to be adjusted longitudinally in relation to the

plates so that they may be made to fit properly on the roller shafts 11, which may be at different distances apart.

When the brake attachment is to be applied to a pair of rollers, the pairs of shoes are arranged the proper distance apart so that they may fit nicely on the shafts of the rollers, and the head 22 of the bolt is then grasped and the lower plate 19 with the shoes 17 turned 5 at right angles to the upper plate, as shown in Fig. 2, thus permitting the lower plate and the lower shoes to be pushed downward between the adjacent roller shafts, and the shoes 17 are then turned back parallel with the 10 shoes 16 and permitted to spring upward against the shafts, after which the shoes 16 and 17 will clasp the two shafts as clearly 15 illustrated in Fig. 3.

By reference to Fig. 4 it will be seen that 20 the upper shoes 16 are longer than the lower shoes and the shoes 16 are longer than the longitudinal movement or stroke of the rollers with which they are connected, so that there is no danger of a shoe 16 dropping down on 25 the journal 12 so as to cause the shoe to prevent the necessary endwise movement of the roller.

It will be seen that the attachment is very 30 simple and inexpensive, that it may be readily applied to the shafts of the rollers, and that it is an easy matter to adjust the tension

of the spring 23 in such a way as to permit the rotation of the rollers and yet stop them as soon as the table passes out of contact with them.

35

Having thus described my invention, I claim as new and desire to secure by Letters Patent—

1. A device of the kind described, comprising opposite plates a spring for pressing the 40 plates together, and shoes longitudinally adjustable on the plates and adapted to clasp parallel shafts, substantially as described.

2. A device of the kind described, comprising an upper and lower plate, the upper plate 45 having a depending middle bend, a spring-pressed bolt secured to the lower plate and slideable in the bend of the upper plate, and brake shoes carried near the ends of the two plates and adapted to clasp parallel shafts, 50 substantially as described.

3. A device of the kind described, comprising opposite plates, a spring for pressing the plates together, and shoes carried by the plates and adapted to clasp parallel shafts, 55 one shoe of each pair being longer than the other, substantially as described.

EMIL MEIER.
